UNITED STATES PATENT OFFICE.

WILLIAM E. DOUGHTY, OF DETROIT, MICHIGAN, ASSIGNOR TO JAMES VERNOR COMPANY, OF DETROIT, MICHIGAN, A CORPORATION OF MICHIGAN.

APPARATUS FOR DISPENSING CARBONATED BEVERAGES.

Application filed February 1, 1926. Serial No. 85,345.

The invention relates to beverage dispensing and refers more particularly to an improved method and apparatus for dispensing carbonated beverages such as ginger ale.

Under the present practice of dispensing ginger ale the beverage is prepared in carbonated condition and for convenience in transporting and storing is placed in suitable containers or tanks subjected to relatively high pressure. Ginger ale in such condition is commonly known as high pressure ale. Heretofore, these tanks of high pressure ale were, before use, placed in an ice packing in order to cool the ale to the desired temperature for drinking. It is also general practice to run the high pressure ale into a settling tank or chamber before drawing off the ale for drinking, the ale in the settling chamber being under relatively low pressure and known as low pressure ale. From the settling chamber the low pressure ale is drawn off for drinking. Thus the settling chamber provides for relief of the greater amount of gas from the ale so that when the ale is drawn from the settling chamber it will not become unduly foamy, a condition which would result if the ale were drawn directly from the high pressure tank to the atmosphere. Heretofore, the high pressure ale tanks and the settling chamber were packed in ice. Where the demand for the ale is relatively large, considerable difficulty and inconvenience has been experienced in cooling down the ale to the desired temperature in keeping with the demand. It has been found for example, that from seven to eight hours is generally required to cool down a high pressure tank of ale of the ordinary ten gallon capacity. Thus, such a dispensing system is not of a flexible character since the supply of properly cooled ale cannot readily be maintained in keeping with a fluctuating demand.

Further difficulty has been experienced in maintaining the ale at the desired temperature at the point of dispensing from the system. For example, during the passage of the ale from the settling chamber, or other source of supply to the point of discharge from the draft apparatus, the temperature is raised by contact with the relatively warm piping and draft apparatus. Such raising

of temperature is especially objectionable and noticeable during the summer months when the draft apparatus and piping leading therefrom to the settling chamber, or other source of supply of cool ale, becomes quite warm. When the ale is drawn intermittently under such conditions, the draft apparatus and piping becomes warm between dispensing periods so that unless the ale is drawn practically constantly it is considerably above the temperature of the ale in the settling chamber or other source of supply.

One of the objects of my invention is to provide a novel method and apparatus for dispensing ale characterized in its ability to efficiently and conveniently cool down a continuous supply of ale avoiding the aforesaid difficulties and objections.

A further feature of the invention resides in the provision of means for quickly cooling the ale to the desired temperature avoiding the aforesaid difficulties and objections under the heretofore general practice of dispensing carbonated beverages.

A still further object of the invention resides in the provision of means whereby the ale is maintained at the desired low temperature during its passage from the supply, such as a settling chamber, to the point of dispensing avoiding the aforesaid difficulties due to contact of the ale with the piping and draft apparatus. Thus the draft apparatus may be located as far as desired from the source of ale and cooling apparatus.

With these and other objects in view, the invention resides in the novel features of construction and combination and arrangements of parts as more fully hereinafter described and claimed.

Referring to the drawings in which like reference characters indicate corresponding parts,

Figure 1 represents an elevation view partly in cross section and diagrammatic to some extent, illustrating one embodiment of my invention; and

Figure 2 is a detail view in section along 3-3 of Figure 1.

In the drawings, reference character A represents a tank or refrigerating chamber having inner and outer walls 10 and 11 respectively with a temperature insulating

medium 12 therebetween, such as cork, for example.

B represents a tank or container providing a source of the liquid to be dispensed 5 described for purposes of illustration as ginger ale, the ale within the tank being carbonated in accordance with general practice and preferably under a relatively high pressure such as one hundred sixty pounds 10 per square inch, for example. For convenience in handling, storage and shipment the tanks B may be of ten gallon size, for example, having a control valve 13 and coupling 14, the latter being adapted to detachably connect with a pipe or conduit 15. The latter pipe is passed through the tank A as shown in Figure 1.

For cooling the ale during its travel through the tank B or other source of supply 20 to the point of dispensing and for maintaining the ale at the desired temperature I might employ cracked ice as shown at 16 in Figure 1. In this form of my invention, the tank A may contain the settling chamber 25 C, referred to hereinafter. The high pressure ale is conducted by a pipe 15' preferably downwardly through the water 17 by the pipe portion 18 to a point substantially at the bottom of the tank. From this point 30 the pipe is coiled upwardly as at 19 through the water to a point substantially adjacent the top of the water whence it passes through the pipe 20 to the settling chamber C. Ice 16, preferably in cracked form, is 35 introduced into tank A, floating on the water.

A feature of my invention resides in providing means for preventing the formation of an insulating film of cold water immediately adjacent the coils 19. To this end, I have provided a propeller agitator or circulating propeller 21 mounted on a shaft 22, the latter being extended through the chamber A by a suitable packed bearing 23. 24 is a motor for rotating shaft 22 and propeller 21 through reduction drive 25 when desired. The propeller agitator 21 driven from shaft 22 is preferably encased in a screen 26 to prevent contact of the ice with 50 the blades of the propeller.

I have found that the temperature of the water at the surface will be substantially 32° F. and at the bottom substantially 40° F. so that by causing the incoming ale to flow 55 upwardly through coils 19 the relatively warm ale is introduced at the bottom of the tank while the relatively cold ale is taken off at the water surface where the lowest temperature of the water is realized.

60 In operation of the system as thus far described, when the ale is conducted from the pipe 20 by any suitable device such as hereinafter set forth, ale to replace that conducted away will flow from the supply tank 65 B to the pipe 15' whence it will be dis-

tributed to the coils 19 for cooling by circulation through the water 17 agitated by propeller 21. The presence of the relatively large body of water 17 serves to stabilize the system preventing fluctuations of temperature within the chamber A. I have found that with fifty feet of one-quarter inch block tin ale conducting pipe, within the chamber A my device described above, can cool forty gallon of ale per hour from 74° F. to 36° F. continuous flow. Such a capacity is sufficient for ordinary purposes and if added capacity is found desirable, the number of coils 19 may be increased or more ice may be added.

80 Preferably within the chamber A and surrounded by the water 17 is a settling chamber C adapted to receive the high pressure ale from the pipe 20 and to afford partial relief of the ale pressure. The ale from pipe 20 passes into the settling chamber C as at 27, the flow being controlled by a pressure regulator 28 of standard or other suitable construction. This regulator 28 may be set to permit flow of ale into chamber C when the pressure in the chamber falls below any predetermined pressure, the latter being ordinarily governed by the head or distance the ale must flow vertically to the point of draft. The latter point is indicated in the 90 drawings by the draft apparatus D shown mounted on counter 29 forming the top of tank A although the draft apparatus may be positioned at any other desired point remote with respect to the tank A, as for example, several floors above the tank. Thus for the relatively small head illustrated in the drawings, the pressure regulator 28 may be set to permit flow of the ale into the chamber C whenever the pressure therein 100 falls below six pounds per square inch.

105 The ale flowing into the chamber C will become foamy, liberating a certain amount of the gas contained in the high pressure ale. In order to permit escape of this gas, to insure a relatively low pressure at all times of the ale in the settling chamber, to afford a proper taste of the ale and to permit the ale to readily settle to liquid form, the following construction is provided.

110 Threadedly engaging an opening 30 in the top of chamber C, preferably above the water line, is a primary valve casing 31, providing a gas chamber 32. The gas from the settling chamber is free to pass to the 115 chamber 32 through port 33 of plug 34, the latter having an axial bore affording a sliding bearing for valve stem 35 of a primary valve 36, the latter controlling the escape of gas from chamber 32 by way of the port 120 37. Connected with the valve stem 35 is a float 38 whereby the primary valve 36 is controlled by the settled or low pressure ale 39 within the settling chamber. 40 is a secondary valve casing connected as by a 125 130

threaded engagement at 41 with the primary valve casing 31, the casing 40 having an inlet port 42 registering with the port 37 affording passage of the gas from chamber 32 to a chamber 43 in the secondary valve casing, the passage of gas thereto being controlled by a secondary valve 44 normally seated by a spring 45. The gas in chamber 43 is free to escape through ports 46 and 47, the latter communicating, by reason of suitable piping, preferably with the atmosphere. The compression of spring 45 may be regulated by rotating the cap 48, forming an abutment for the spring, at the point of threaded engagement 49 with casing 40.

I have found it desirable, for example, to arrange the spring 45 to act to seat the secondary valve 44 whenever the pressure of the gas in the settling chamber falls below two pounds per square inch, such pressure establishing a minimum for the ale in the settling chamber. When ale is drawn from the settling chamber the float 38 lowers unseating valve 36. If the pressure in the settling chamber is less than six pounds per square inch, high pressure ale will flow into the chamber C past regulator 28 from pipe 20. Whenever the pressure of ale in chamber C is more than two pounds per square inch, and the valve 36 unseated, the excess pressure passes from chamber C to primary valve chamber 32 past valve 36 and ports 37 and 42 to the secondary valve chamber 43, whence it acts to unseat secondary valve 44, the gas then escaping to the atmosphere by way of ports 46 and 47.

It will thus be noted that I have provided a control device whereby there will be at all times from two to six pounds per square inch pressure on the low pressure settle ale in the settling chamber C. Heretofore, "pop" valves were used to liberate the settled ale, these valves frequently becoming worn so as to leak, liberating all the gas from the settled ale and thus leaving the ale with a "flat" undesirable taste.

With my invention, the escape of the gas from the settling chamber is positively controlled by the height of the ale and when the valve 36 is unseated, then the valve 44 will operate to liberate gas in excess of two pounds per square inch pressure. Even if the valve 44 should leak, there is always a relatively large amount of gas being liberated by the inflowing high pressure ale and when the ale level rises, the valve 36 will positively close, thus trapping the remaining liberated gas from the ale in the settling chamber. There will always be a pressure on the settled ale of from two to six pounds per square inch. When the valve 36 closes, the regulator 28 will function as at other times to build up the pressure to six pounds per square inch.

As shown in Figure 1, the settling cham-

ber C is preferably located within the tank A and nearly entirely surrounded by the cooling water 17. The propeller 21 serves to maintain the temperature of the water in the vicinity of chamber C, the same as the temperature in the vicinity of the coils 19.

The ale from the chamber C is drawn off to the draft apparatus D by a pipe 50 preferably communicating with the chamber at the bottom where the surrounding cooling water is of the lowest temperature. The draft apparatus D comprises the draft arm 51 terminating in the draw-off spout or nozzle 52 controlled by a valve 53. As aforesaid, the regulator 28 may be set to correspond with the pressure necessary to force the ale up to the valve 53, the head being relatively low as shown in the drawings.

In order to maintain the temperature of the ale in the draft arm 51 equal to that in the chamber C, I have provided means for circulating the cold ale from the settling chamber to the draft arm so that as soon as valve 53 is opened, ale will be drawn from nozzle 52 at the temperature of the ale in the chamber B. To this end, a circulating pipe 54 is connected preferably between the bottom of chamber C and a circulating pump E actuated preferably by the shaft 22. This pump forces the ale through pipe 55 which has a portion 56 extending along the surface of the water further serving to maintain the desired low temperature of the ale drawn to the dispensing apparatus. Thence the ale passes upwardly into the draft arm 51, the circulating pipe being open-ended so as to pass the cold ale from chamber C to a point adjacent the valve 53. Thus this circulating pipe will cause a continuous flow of cold ale upwardly through the pipe portion 56 and downwardly through the draft arm 51 and pipe 50 to the chamber C. Thus, even though the ale is drawn from the nozzle 52 at intermittent periods, the ale drawn will always be of a temperature the same as the ale in the chamber C. It will further be noted that the draft apparatus D may be located remotely from the chamber C or other source of cold ale, at the same time insuring properly cooled ale when drawn from the dispensing nozzle. I have thus avoided the objection of drawing ale warmed during passage from the source of supply to the dispensing nozzle.

While it is believed from the foregoing description, the nature and advantage of my invention will be readily understood, I desire to have it understood that I do not limit myself to what is herein shown and described and that such changes may be resorted to when desired as fall within the scope of the claims.

What I claim as my invention is:—

1. A carbonated beverage dispensing ap-

130

paratus comprising a tank adapted to contain a cooling liquid, means for conducting the beverage within the tank from a source of supply without the tank, a pipe connected to receive the beverage within the tank and arranged in a circuitous path below the level of the liquid in the tank, means for cooling the liquid, a settling chamber also located within the tank, means for conducting the cooled beverage from the said circuitous pipe to a point within the settling chamber, a draft apparatus located without the chamber, means for conducting the beverage from the settling chamber to the draft apparatus, means for circulating the beverage between the draft apparatus and the said chamber, said last named means including a pump, a rotatable shaft for actuating said pump, and means also actuated by said shaft for establishing a circulation of the said liquid within the tank.

2. A beverage dispensing apparatus including in combination a beverage chamber, a draft apparatus, a pump for circulating the beverage between the said draft apparatus and the chamber, means for actuating said pump, and means actuated by said pump actuating means for circulating a cooling medium around the said chamber.

3. A beverage dispensing apparatus including in combination a beverage chamber, a draft apparatus, a pump for circulating the beverage between the said draft apparatus and chamber, means for actuating the said pump, and means for circulating a cooling medium around the said chamber, said last mentioned means including a propeller,

and a driving connection between the said propeller and the said pump actuating means.

4. A beverage dispensing apparatus including in combination a beverage chamber, a draft apparatus, a pump for circulating the beverage between the said draft apparatus and chamber, a shaft for actuating the said pump, and a propeller mounted on the said shaft and driven thereby for circulating a cooling medium around the said chamber.

5. In combination, a tank adapted to receive a mixture of ice and water, a settling chamber within the said tank, a draft apparatus connected to the said settling chamber, a pump for circulating the beverage between the said draft apparatus and chamber, a shaft for actuating the said pump, a propeller on the said shaft for circulating the mixture of ice and water around the said chamber, and means for shielding the said propeller from the ice.

6. In combination, a tank adapted to receive a mixture of ice and water, a settling chamber within the said tank, a draft apparatus connected to the said settling chamber, a pump for circulating the beverage between the said draft apparatus and chamber, a shaft for actuating the said pump, a propeller on the said shaft for circulating the mixture of ice and water around the said chamber, and means for shielding the said propeller from the ice, said means including a screen secured to the said tank and forming a housing around the said propeller.

In testimony whereof I affix my signature.
WM. E. DOUGHTY.
